Attorney.

UNITED STATES PATENT OFFICE.

CHARLES E. SCRIBNER, OF CHICAGO, ILLINOIS, ASSIGNOR TO THE WESTERN ELECTRIC COMPANY, OF SAME PLACE.

NATURAL-GAS PROTECTIVE EXTINGUISHER.

SPECIFICATION forming part of Letters Patent No. 393,396, dated November 27, 1888.

Application filed June 1, 1888. Serial No. 275,750. (No model.)

To all whom it may concern:

Be it known that I, CHARLES E. SCRIBNER, a citizen of the United States, residing at Chicago, in the county of Cook and State of Illinois, have invented a certain new and useful Improvement in Natural-Gas Protective Extinguishers, (Case 152,) of which the following is a full, clear, concise, and exact description, reference being had to the accompanying drawings, forming a part of this specification.

In supplying gas for heating and illumination it is desirable that the pressure should be maintained as nearly constant as possible. In case of natural gas, especially, it has been found impracticable to at all times maintain a constant and uniform flow of the gas. When the pressure suddenly falls, as it frequently does, the gas is extinguished, and, the pressure thereafter being increased, the gas escaping fills the building, until, finally, the escaped gas, becoming ignited, explodes. Accidents of this sort have been of frequent occurrence heretofore, and on this account natural gas especially, which is highly explosive, has not found the favor with the public which it might otherwise have obtained.

The object of my invention is to provide for automatically shutting off the gas when for any reason the pressure falls so low as to extinguish the flame. In this manner the flow of gas is checked and all danger of explosions is avoided.

My invention consists in electro-magnetic apparatus so combined with the gas-pipes and the flame that on extinguishing the flame the apparatus will be operated automatically to cut off the gas supply.

I have in the accompanying drawings illustrated one form of apparatus embodying my invention, in which

Figure 1 is a side elevation of my automatic gas-extinguisher apparatus, and Fig. 2 is a plan view of the same.

The gas-pipe *a* may be considered as connected with the mains and of sufficient size to supply a dwelling-house. In this gas-pipe is placed a cock or shut-off, *b*.

My invention is designed to furnish ready means of automatically closing a cock *b* when for any reason the flame *c* is extinguished—

as, for example, when the pressure falls suddenly much lower than the normal. In this manner the gas is shut off, and hence if the pressure is increased again no damage will be occasioned. The thermostat *d* is so constructed and arranged with respect to the flame or jet *c* that as long as the jet is burning its contacts will remain open, as shown. When the jet is extinguished, however, the contacts will close.

The form of thermostat which I have shown consists of springs each composed on opposite sides of metals—as, for example, zinc and copper—having unequal coefficients of expansion when heated. I do not, however, limit my invention to any particular form of thermostat, since there are various thermostats well known in the art which might be employed with equally good results.

The cock *b*, as shown, is open. The arm *e*, which is attached to cock *b*, is preferably weighted, its weight being sufficient, in connection with retractile spring *f*, to turn the cock when said arm is released, so as to shut off the supply, the arm when so released falling to the position indicated by the dotted lines in Fig. 1. This weighted arm is normally held in the position shown by catch *g* upon an armature lever of an electro-magnetic device. The coils of the electro-magnetic device are included in circuit with a battery, *h*, and a thermostat, *d*. In this circuit is also preferably included the arm *e* and the catch *g*, in order that the circuit may be opened, when the arm is allowed to fall. As long as the jet *c* continues to burn, the thermostat *d* remains open, and hence the circuit of battery *h*, through the coils of electro-magnet *i*, will remain open at the thermostat. Supposing, now, the gas should be momentarily cut off or the pressure diminished sufficiently to extinguish the jet *c*, the thermostat becoming cold immediately, its contacts will come together, thus closing the circuit of battery *h* through the coils *i*. The circuit being thus closed, the armature carrying the catch *g* will be moved so as to release the arm *e*. Thereupon the cock *b* will be turned, the spring *f* being preferably employed in connection with the weighted arm *e*. As soon as the arm *e* separates from the catch *g* the circuit will be again broken. A weighted arm or

drop *e* might be used alone, or a spring *f* of sufficient strength, without departing from my invention.

It will be understood that the gas jet *e* should be supplied from the pipe *a* in such position and under such conditions that it will surely be extinguished when any other jet supplied from the same pipe is extinguished.

Having thus described my invention, I claim

as new and desire to secure by Letters Patent—

1. A gas protective extinguisher consisting of a cock or shut-off in the supply-pipe, in combination with a gas-jet supplied from said pipe, a thermostat placed in position to be heated by the jet, actuating mechanism for turning the cock or shut-off, and an electro-magnetic device in a battery-circuit with the thermostat, whereby on extinguishing the jet the electro-magnetic device is operated to release the actuating mechanism, substantially as described.

2. The combination, with the gas supply pipe, of a cock or shut-off included therein, actuating mechanism for closing said shut-off,

an electro-magnetic device normally retaining or holding out of operation the said actuating mechanism, a gas jet supplied from the said gas supply pipe, a thermostat in position to be heated thereby, and a battery-circuit through the electro-magnetic device, which is closed when the jet is extinguished, substantially as described.

3. The combination, with the supply-pipe *a*, of a jet, *e*, supplied from said pipe, a thermostat heated by said jet and standing normally open when heated, a shut-off included in said supply-pipe, and an electro-magnetic device whereby said shut off is operated when the jet is extinguished and the contacts of the thermostat closed, the circuit of the electro-magnetic device being opened by the closing of the shut-off, substantially as described.

In witness whereof I hereunto subscribe my name this 2d day of May, A. D. 1888.

CHARLES E. SCRIBNER.
